UNITED STATES PATENT OFFICE.

ARTHUR LANCIAULT, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

MOUNTING FOR PICKER SPINDLES.

Application filed October 4, 1923. Serial No. 666,635.

This invention relates to spindle picking of the type usually found on the drop box ends of fancy looms and the general object of the invention is to provide an improved 5 mounting for the picker spindle usually found on this type of loom.

Looms of the type referred to employ several shuttles mounted for vertical movement on the lay and in order to propel the various 10 shuttles there is usually provided a picker one end of which extends behind the active shuttle and the other end of which is elongated and provided with a bore by means of which it is mounted on the picking spindle. 15 The picker stick acts on the picker at some point between the boxes and the spindle.

In such a construction the picking spindle is subjected to considerable longitudinal strain and the usual method of mounting 20 the spindle has been to support the inner end on some part of the lay end while the outer end is received by a support bolted or otherwise secured to the lay. A set screw carried by the support secures the outer end 25 of the spindle so that the latter is held in fixed position with respect to the lay. However, the jar incident to the normal operation of the loom is such that the set screw is likely to wear loose and to prevent accidental removal of the spindle from the loom 30 there is usually provided an auxiliary retainer to engage the outer end of the spindle when the latter is loose.

The general object of my invention is to 35 provide a single holding means associated with the support by means of which the spindle will not only be held rigidly in place with respect to the lay but should the spindle become loose this same means will serve 40 to prevent accidental removal thereof from the loom.

With this general object in view and others which will appear as the description proceeds the invention resides in the combination and arrangement of parts herein-after described and pointed out in the claim.

In the drawings wherein a preferred form 50 of the invention is shown Fig. 1 is a top plan view of a lay having the invention applied thereto,

Fig. 2 is an enlarged rear elevation of the

lay taken in the direction of arrow 2, Fig. 1, and

Fig. 3 is a horizontal section taken on line 55 3—3 of Fig. 2.

Referring to the drawings, the lay 10 is shown as provided with the usual guides 11 and 12 between which are mounted the boxes 13 carrying shuttles 14. The lay is provided with the usual lay end 15 carrying a lug 16 which receives the inner end of a picking spindle 17. The outer end of the spindle is received by a support 18 secured to the lay end by means of bolt 19. The support 18 abuts two sides of the usual lay end flange and the single bolt 19 is sufficient to hold it from relative motion with respect to the lay.

A picker 20 is mounted to slide on spindle 70 17 and has the inner end 21 thereof in horizontal alignment with the shuttle opposite the shuttle race.

The matter thus far described is of the usual construction and it is to be understood 75 that the form of support 18 may vary with different types of looms.

My improvements are concerned with the method of supporting the outer end of the picking spindle and it will be seen by referring to Figs. 2 and 3 that support 18 is provided with a clear hole 22 through which the picking spindle 17 passes. Aligning with the opening 22 is a threaded bore 23 which receives a screw 24 so arranged as to 80 have the inner end thereof in contact with the spindle 17. A lock nut 25 is preferably employed to hold the screw 24 in adjusted position and if desired this nut may be provided with a cap 26 to cover the outer end 90 of screw 24 and serve as a shield therefor.

When applying my invention to a loom the screw 24 is removed from the bore 23 and the spindle 17 inserted through the aligning openings in the support 18, the 95 spindle being moved until the inner end thereof is supported in lug 16. The screw 24 is then inserted in the bore 23 and set up tightly against the spindle after which the lock nut is applied.

It will be observed that it is necessary to have the bore 23 of a diameter at least equal to the diameter of the spindle in order that the latter may pass through the support 18.

It will also be observed that the single screw 24 serves not only to hold the spindle 17 tightly in place but should the latter work loose for any reason, the screw will still serve to prevent accidental removal of the same from the loom. It occasionally happens that support 18 works loose with respect to the lay and under former construction where this support was held tightly to the spindle both the support and spindle were subject to inward motion at the time of picking but with the present construction the spindle may move inwardly with respect to the support 18 without moving the latter 15 inasmuch as the spindle moves freely in opening 22.

Having described one form of my invention it will be apparent that changes and modifications may be made by those skilled 20 in the art and I do not wish to be limited to

the particular structure set forth, but what I do claim is:—

In a mounting for a picker spindle for a loom having a lay, the picker spindle having the inner end supported on the lay, a support for the outer end of the spindle mounted on the lay and having an opening therethrough aligned with the spindle and of sufficient size to permit the spindle to pass freely therethrough, said spindle extending 25 into and terminating between the ends of the opening, a screw of larger diameter than the spindle threaded into the outer end of the support to restrain longitudinal movement of the spindle, and means to lock said 30 screw in holding position with respect to the spindle and support.

In testimony whereof I have hereunto affixed my signature.

ARTHUR LANCIAULT.
